(57) **CLAIM**

The ornamental design for a display panel or screen with animated graphical user interface as shown and described.

DESCRIPTION

FIG. 1 is a front view of a display panel or screen with animated graphical user interface showing a first image of our new design; and,

FIG. 2 is a front view of a second image thereof.

The appearance of the animated image sequentially transitions between the images shown in FIG. 1 and FIG. 2. The process or period in which one image transitions to another forms no part of the claimed design. The evenly-spaced broken lines depict portions of the display panel or screen with animated graphical user interface that form no part of the claimed design. The dot-dash broken lines define the boundary of the claimed design. The dot-dash broken lines form no part of the claimed design.
